LLP**CLAIM**

The ornamental design for a display screen of a centrifuge with graphical user interface, as shown and described.

DESCRIPTION

The sole FIGURE is a front view of an embodiment of my new display screen of a centrifuge with graphical user interface design.

The rectangle shown in broken lines illustrates the display screen of a centrifuge. The words, symbols and numbers shown in broken lines illustrate unclaimed features of the graphical user interface applied thereto. The broken-line subject matter forms no part of the claimed design.

1 Claim, 1 Drawing Sheet---
